DESIGN FOR A COMBINED SPOUT AND CLOSURE FOR BOTTLES

Arthur B. R. Rothwell, Lisheen, Danbury, near
Chelmsford, England

Application February 26, 1940, Serial No. 90,539

Term of patent 14 years

To all whom it may concern:

Be it known that I, Arthur B. R. Rothwell, a subject of the King of Great Britain, residing at Lisheen, Danbury, nr. Chelmsford, Essex, England, have invented a new, original, and ornamental Design for a Combined Spout and Closure for Bottles, of which the following is a specification, reference being had to the accompanying drawing, forming a part thereof.

Figure 1 is a side elevational view of the article, showing my new design; Figure 2 is a perspective view of the same; and Figure 3 is a bottom plan view thereof.

I claim:

The ornamental design for a combined spout and closure for bottles, as shown.

ARTHUR B. R. ROTHWELL.
